DESIGN FOR A STOCKING

Jacob A. Goodman, Indianapolis, Ind., assignor to National Silk Hosiery Mills, Inc., Indianapolis,
Ind., a corporation of Indiana

Application March 21, 1939, Serial No. 83,729

Term of patent 3½ years

To whom it may concern:

Be it known that I, Jacob A. Goodman, a citizen of the United States, residing at Indianapolis, in the county of Marion, State of Indiana, have invented a new, original, and ornamental Design for a Stocking, of which the following is a specification, reference being had to the accompanying drawing, forming a part thereof.

The figure is a rear view of the upper portion of a stocking embodying my design, the foot, leg and ankle portions being somewhat in perspective.

The new design is characterized by the panel contrasting with the fabric of the adjoining portions centering on the middle line of the stocking back, the panel tapering in its lower part and extending vertically upward through the upper portion of the stocking as shown:

I claim:

The ornamental design for a stocking, as shown and described.

JACOB A. GOODMAN.
